CANDLE EXTINGUISHER

Bernard A. Benziger, South Orange, N. J., assignor to Benziger Brothers, New York, N. Y., a firm composed of Xavier N. Benziger, Alfred F. Benziger, and Bernard A. Benziger

Application May 23, 1933. Serial No. 672,519

4 Claims. (Cl. 67—75)

This invention relates to candle extinguishers and is particularly adapted to be used in churches or other high ceilinged buildings which are illuminated with or decorated by lights of candles. It is one of the objects of the invention to provide means which can be extended to extinguish candles which are considerably beyond the reach of the attendant. Another object is to provide such means with a cap that can be disposed over or above the candle flame proper and by virtue of its shape and location of air openings will effectively snuff out the flame. Further objects will become apparent after a perusal of the following specification and an inspection of the accompanying drawing, in which

Fig. 1 is an elevational view of an extinguisher embodying a cap built according to the principles of my invention;

Fig. 2 is an enlarged longitudinal sectional view through the cap proper; and

Fig. 3 is a cross sectional view along the plane of line 3—3 in Fig. 2.

Like characters denote similar parts throughout the several views and the following specification.

10 is a tubular bottom member having a rubber bulb 11 in its center, and a cap 12 at its lower end provided with a loop 13 for convenient hanging. The top of member 10 has fastened to it an annular sleeve 14 bearing a set screw 15. 16 is a tubular intermediate member telescoping into bottom member 10 and having an annular sleeve 17 at its top, bearing a set screw 18. 19 is a tubular top member adapted to telescope into intermediate member 16. Fastened alongside of top member 19 by means of bands 20 is a smaller tubular member 21 containing a wax taper 22 adapted to be raised or lowered by a movable socket having an outwardly extending knob 23 in the manner well known in the art. The upper portion of top member 19 is curved downwardly to receive an extinguisher cap 24. This cap is substantially cone-shaped and has a socket 25 threaded internally to screw upon a correspondingly threaded end of the top member 19. A conical outer wall 26 of sheet metal is secured to socket 25 with its small end, its large end being slightly bent over at 27. 28 is an inner wall of sheet metal fastened with its flattened central portion 29 to the bottom of socket 25, disposed in spaced relation to outer wall 26, and bent over at its bottom at 30 to engage air tightly portion 27 of outer wall 26, thus forming a chamber 31 between the two walls. Socket 25 is provided with orifices 32 in its sides immediately adjacent the

portion 29 of the inner wall, and 33 is an orifice, preferably central with socket 25, through this portion 29. A number of very small perforations 34 are provided for in the inner wall 28 of the cap.

The operation of the device is as follows:

The tubular members 10, 16 and 19 are extended to a suitable length and there fixed by adjusting screws 15 and 17. The cap 24 is then brought into a position above the flame of the candle. Squeezing bulb 11 will cause air to be forced through tubular members 10, 16 and 19, and thence through orifice 33 against the flame. Simultaneously air passes through orifices 32 in socket 25 into air chamber 31 and is forced out through the small perforations 34. Orifice 33 being much larger than perforations 34, a strong jet of air is projected directly against the flame, while the small jets of air projected from the perforations 34 tend to blow against the flame should the cap be placed slightly around the flame. The combined air jets, issuing from the cap, by virtue of its cone-shaped inner wall 28 are directed against the flame and their force concentrated thereupon, effectively extinguishing the same.

Practical tests have proven that it is not necessary to place the cap directly over and around the flame to extinguish the same, but the same may be disposed at some distance above it, the cone shape of the cap, as explained above, directing the air currents with sufficient force against the flame. It is also obvious that while I have shown a cap having a double wall for the purpose of directing air jets laterally into the conical cap, I may, if I so desire, eliminate the double wall and its perforations, and use a single walled cone-shaped cap and depend upon central orifice 33 aided by the confining conical wall of the cap to extinguish the flame of the candle.

I want it to be understood that other changes in the form, proportion and minor details of construction may be resorted to without departing from the principles or sacrificing any of the advantages of the invention, as defined in the appended claims.

What I claim as new is:

1. In a candle extinguishing device, a conical cap adapted to be placed over the flame of a candle, and means to force air into the central part of the cap through orifices at the small end and the sides of the cap, the shape of the said cap serving to direct the air toward the said flame.

2. A cap for candle extinguishing apparatus of substantially conical shape having an outer wall and an inner wall forming an air chamber, and

means to secure the said cap to an air tube, the said cap having orifices to admit air from the said tube into its central part, the conical shape of the said cap serving to direct air from the said orifices against the flame of a candle.

3. A cap for candle extinguishing apparatus of substantially conical shape having an outer wall and a perforated inner wall forming an air chamber, a socket at its small end adapted to 10 screw onto an air tube, and having orifices to admit air from the said tube into the said chamber, and an orifice admitting air directly into the

central part of the cap, the inner wall of the said cap serving to direct air from the said orifices against the flame of a candle.

4. In a candle extinguishing apparatus, a conical cap adapted to be placed over the flame of a candle, and means to force air into the central part of the cap through a relatively large orifice at its small end and relatively small orifices at its sides, the shape of the said cap serving to direct the air from the said orifices toward the said flame.
